BASEBOARD CONSTRUCTION

William C. De Roo, Holland, Mich., assignor to Hart & Cookey Manufacturing Co., Holland, Mich., a corporation of Delaware

Application June 14, 1951, Serial No. 231,535

8 Claims. (Cl. 98—49)

This invention relates in general to a novel construction of baseboard located adjacent the wall of a room at the floorline thereof and is particularly directed to a form of baseboard adapted for use in connection with the perimeter heating of a room.

The trend toward placing the source of heat in a room or building toward the outside walls thereof has made it desirable to use forced air as a transmitter of the heat from the furnace to the area to be heated. It has also been found advantageous to have the air distributed as evenly as possible at the place of entering the room along the baseboard of the entire wall.

Heretofore, various types of registers have been designed which were inserted into a standard baseboard and which directed the air up against the wall in an arc. Such a procedure, however, obviously did not result in an even distribution of the air along the entire wall. There have also been attempts in the past to construct baseboards which would distribute the air evenly along the entire wall, but in those cases there have been many construction difficulties experienced which has prevented their ready adoption by the public.

It is, therefore, a principal object of the present invention to provide a novel baseboard construction which will act to distribute the air evenly along the entire wall of a room and which is designed to overcome the construction difficulties mentioned hereinabove, thereby enabling the ready adoption thereof by the public.

Another object of the invention is to provide a novel baseboard construction adapted for use in connection with the perimeter heating of a room wherein air will be distributed evenly over an entire wall from a forced air source.

A further object of the invention is to provide a baseboard construction adapted to be readily installed at the juncture of the floor and wall of a room and which may be easily adjusted along the length thereof so that air entering the room through an opening or openings therein will be evenly distributed along the entire wall.

Still another object of the invention is to provide a novel baseboard construction for perimeter heating which will adapt itself readily for installation at the juncture of the floor and wall of a room whether the wall be of the conventional lath and plaster type or may be of wall or plaster board.

A still further object of the invention is to provide a novel baseboard construction for perimeter heating which is formed of two members having a space therebetween for the passage of air from a forced air source into the room and wherein the space between the two members may be readily adjusted to cause an even distribution of the air along the entire wall.

Still another object of the invention is to provide a novel baseboard construction for perimeter heating wherein a backplate may be located between the floor and wall of a room and secured to the wall studs and wherein a faceplate consisting of two spaced apart members is adapted to be located along the length of the wall

2

in spaced relation to the backplate whereby the space between the backplate and the faceplate will form a conduit for air and the space between the two members of the faceplate will permit the air to pass therethrough into the room.

Still another and more specific object of the invention is to provide a baseboard construction for perimeter heating wherein a backplate is provided and secured to the wall studs and terminating in an upper longitudinal edge and an inwardly extending lower edge. The lower edge is set at the floor to the height of the expected finished flooring. The upper edge underlies the bottom edge of the wall lath and has a portion thereof protruding inwardly, thereby enabling it to act as a plaster guide permitting the plasterer to strike against it and finish the plaster smoothly along its lower edge.

A still further object of the invention is to provide a baseboard construction for perimeter heating wherein a backplate extends along the length of the wall at the bottom edge thereof and between the wall and the floor, and wherein a faceplate formed of two spaced apart members is adapted to be releasably held in place against the wall and the floor by fastening means either secured to or formed as an integral part of the upper and lower edges of the backplate.

Another object of the invention is to provide a novel form of adjusting means for regulating the space between the two members forming the faceplate to enable the air passing through the space therebetween to be distributed evenly over the entire wall.

Still another and specific object of the invention is to provide a baseboard construction for perimeter heating wherein a plurality of openings for the passage of warm air are so arranged as to permit air to be forced outwardly parallel with the floor in addition to the air passing upwardly along the wall.

Other objects and advantages of the invention will become apparent upon reading the following description taken in conjunction with the accompanying drawings in which:

Fig. 1 is a vertical sectional view through the wall and floor of a room and illustrating one form of baseboard construction embodying the present invention, and taken along line 1—1 of Fig. 3;

Fig. 2 is a somewhat enlarged horizontal sectional view of the adjusting means taken along line 2—2 of Fig. 1;

Fig. 3 is an elevational view of the baseboard embodying the present invention showing the floor and air conduit in section;

Fig. 4 is a view similar to Fig. 1 but illustrating a modified form of the invention, and taken along line 4—4 of Fig. 6;

Fig. 5 is a horizontal sectional view taken along line 5—5 of Fig. 4;

Fig. 6 is an elevational view of the baseboard illustrated in Fig. 4 with parts broken away and parts in section for the sake of clarity;

Fig. 7 is a fragmentary view similar to Fig. 4, but showing a further modification; and

Fig. 8 is a fragmentary elevational view of the modification shown in Fig. 7.

Briefly described, the invention herein contemplates the use of a baseboard construction for perimeter heating wherein one or more air conduits or stacks from a furnace may communicate with the interior of the baseboard construction. The invention includes a backplate which may have one or more openings cut therein so that the stack or stacks from the furnace may be fixed thereto. The faceplate of the baseboard is formed of two members mounted in spaced apart relation. The upper member is adapted to be removably secured adjacent the lower part of the wall by means of a base-

board retainer. The lower member is removably secured adjacent the edge of the floor by means of a curled lip formed integral with the forward edge of the backplate. The upper member of the faceplate extends downwardly to a point below the upper edge of the lower member. The upper and lower members of the faceplate are thus in overlapping and spaced relation so that air directed through the opening in the backplate may be distributed along the wall behind the faceplate and will pass into the room through the space between the upper and lower members of the faceplate.

It will be evident that more air will tend to pass into the room in the immediate vicinity of the connection of the stack with the backplate than elsewhere along the length of the baseboard. In order to prevent this occurrence, adjusting means have been provided to regulate the space between the two members of the faceplate so that, if desired, they may be adjusted closer together immediately adjacent the stack and farther apart on each side thereof, thereby to allow the air coming from the stack to be more evenly distributed along the baseboard.

Referring now more particularly to the drawings and especially to Figs. 1, 2 and 3, the numeral 1 is used to indicate the finished floor of a room and 2 indicates the subfloor. As is customary in dwellings, a stack 3 may extend from a furnace below the floor and terminate above the floorline in a stackhead 4. The particular wall construction illustrated in Fig. 1 is formed of lath and plaster wherein the lath is indicated at 5 and the finished plaster wall at 6.

The invention herein embodies a backplate generally indicated at 7 which terminates at its upper edge in a forwardly extending portion 8 and a downwardly extending lip 9. While the backplate 7 may be formed of any desired or suitable cross sectional configuration, it has been found practical to make this backplate with a rear portion 10 adapted to be positioned substantially vertically and a lower forwardly extending portion 11 adapted to be positioned substantially in a horizontal plane and to have its forward edge terminate adjacent the edge of the floor 1. The forwardly extending part 8 at the top of the backplate is adapted to abut against the under edge of the lath, thereby permitting this part of the backplate to act as a plaster guide so that the plasterer will have something to strike against, thereby resulting in a smooth finish of the plaster wall all along the bottom edge. The backplate 7 is adapted to be secured to the wall studs 12 by any suitable means such as nails 13. In order to attach the stackhead 4 to the backplate 7 and to permit air from the furnace to be directed through the backplate, an opening 14 is cut into the rear side and bottom thereof. The opening 14 is substantially the size of the opening of the stackhead and the two members are secured together by bending ears such as shown at 15, 16 and 17 on the stackhead around the edges of the opening in the backplate. The ears 15 and 16 are located at each end of the opening 14 and the ear 17 is bent back over the upper edge of the opening. Similar ears 18 (Fig. 1) are bent back over the portion of the opening extending horizontally as shown at 11.

When the stackhead 4 is thus secured in place to the backplate 7, warm air coming from the furnace will be directed through the opening 14 in the backplate.

The baseboard construction of the present invention also includes a faceplate generally indicated at 19 and comprises an upper member 20 and a lower member 21. The upper member 20 extends forwardly a short distance from a point adjacent the lower edge of the plastered wall 6 and then downwardly as at 22. The lower member 21 of the faceplate extends upwardly from the floorline in spaced relation to the portion 22 of the upper member 20 and in overlapping relation therewith. The upper longitudinal edge of the bottom member 21 is preferably bent rearwardly at an angle as indicated at 23.

The upper and lower members 20 and 21 of the base-

board assembly are held together by suitable means which may be adjusted to regulate the space between the two members. While any suitable means may be used for this purpose, it has been found advantageous to use a yieldable member such as a spring indicated generally by the numeral 24 in Fig. 2. The particular form of spring disclosed herein comprises wings 25 and 26 positioned in diverging relation between the overlapping and spaced portions 21 and 22 of the baseboard assembly. A flat portion 27 connects the two wings 25 and 26 and has an opening therethrough in alignment with a similar opening in the lower baseboard member 21 for the reception of a screw 28. The screw extends between the members 21 and 22 and is received by an opening in the inner member 22.

There is preferably a plurality of these yieldable adjusting members 24 spaced along the length of the baseboard assembly at any desired distance apart. The yieldable member 24 consisting of the wings 25 and 26 will bear against the inner surfaces of the upper and lower members 20 and 21 of the baseboard assembly and will hold these members rigidly in spaced apart relation. It will be evident that the space between the portions 21 and 22 of the baseboard faceplate may be regulated by turning screw 28 and the two members will be maintained in the adjusted position by means of the yieldable spring member 24. The dotted line position of the upper and lower members 20 and 21 illustrated in Fig. 1 shows the position of the two members when the screw 28 has been turned to move the two members farther apart, thereby providing a greater space between them.

The entire faceplate assembly is removably mounted in a very simple manner against the wall and floor of the room. The upper rear edge of the upper member 20 is bent downwardly as at 29 and is adapted to be received between the wall and a retaining member 30. This retaining member 30 is yieldable and has the lower end thereof secured to the downturned portion 9 of the backplate. There may be a plurality of these retaining members 30 spaced apart through the length of the backplate in order to yieldably hold the faceplate assembly against inadvertent movement.

The lower edge of the lower member 21 extends rearwardly as at 31 and is preferably provided with a curled lip 32 adapted to be received under the forward bottom edge of the backplate. The forward bottom edge of the backplate is preferably bent upwardly and then downwardly to provide a recess into which the curled lip 31 may be received. Since the upper and lower members of the faceplate assembly are rigidly secured together by means of the yieldable members 24, the entire assembly will be maintained in place by means of the retaining members 30 at the top thereof and the forward edge of the backplate at the bottom thereof.

It will be understood that the heating loss of the room and the length of the wall determines the number of stacks necessary in any given installation. A single stack may be sufficient if the heating loss is low and the length of the wall to be heated is not very great. Lower walls as well as greater heat loss would require perhaps two or more such stacks. In using the present invention, however, the number of stacks is an unimportant detail from the structural standpoint because an opening may be cut in the backplate to accommodate each stack.

It will also be apparent that a greater amount of warm air will tend to escape into the room through the space between the two members comprising the faceplate in the immediate vicinity of the stack than elsewhere along the length of the baseboard. The adjustable feature above described, whereby the space between the two members of the faceplate can be adjusted, will enable this space in the vicinity of the stack to be made smaller than at other locations along the length of the baseboard. Thus, as the air enters the conduit formed by the backplate and

faceplate, it will be distributed along the length thereof in such a way that substantially the same amount of warm air will enter the room through the space between the faceplate members at all points along its length.

The baseboard construction embodying the present invention is also adaptable for use in connection with the so-called "dry wall" construction where the thickness of the plaster coating in the lath and plaster construction is eliminated. The present baseboard assembly being adapted for use with a "dry wall" construction will also eliminate the necessity for carrying a separate type of heating unit or register in the absence of a lath and plaster construction. All that is necessary in this instance is to provide a spacer strip behind the baseboard retainer members and then assemble the faceplate against the "dry wall" in a similar manner, above described, with respect to the plaster wall.

Figs. 4, 5 and 6 illustrate the use of the present invention as applied to a "dry wall" construction. In these figures, similar reference numerals have been used to identify similar parts. The same stack arrangement may be used and secured to the backplate 7 in the same manner by bending the ears of the stackhead around the edges of an opening cut into the backplate. The backplate is provided with the same forwardly extending portion 8 at the upper edge thereof and the downward extension 9 to which the retainers 30 are fixed. Since the layer of plaster is eliminated in this construction, there will be but a single thickness of the "dry wall" as indicated at 33. A spacer strip 34 is located on top of the forward extension 8 and is held in place by the retainers 30. The downwardly extending lip 29 at the rear edge of the upper member indicated in Fig. 4 as 20a will be located against the wall 33 and behind the spacer strip 34.

Other than the foregoing, the construction may be identical with that previously described wherein the lower member 21 of the faceplate is rigidly secured to the upper member 20a by means of the resilient adjustable member 24 and the screw 28. There being a plurality of these adjustable members 24 spaced along the length of the baseboard, the screw of each one may be individually adjusted to regulate the space between the two members of the faceplate in order that the air passing therebetween may be evenly distributed along the length of the wall.

It has also been found advisable in certain instances, where it is desired that a greater amount of air reach the space between the members with less resistance, to place a series of holes in that part of the upper member 20a which is in overlapping relation with the lower member 21. In this connection it may be stated that in the ordinary and preferred construction the air directed against the rear side of the faceplate must find its way to the space between the upper end lower members by passing below the bottom edge of the upper member. This creates a certain amount of resistance and it is for this purpose that a series of openings 35 may be placed in the upper member 20a. These openings are illustrated in Figs. 4, 5 and 6 as being circular and located in a double row relatively close together. It will be obvious, however, that the shape, size and number of the openings may vary to suit particular purposes without in any way departing from the spirit of the invention.

It will be noted that the adjustability feature of the invention, whereby the amount of air passing into the room may be regulated, will still be effective even with the openings 35 present, since they are located below the actual passage between the two members of the faceplate through which the air passes.

A still further feature embodied in the present invention which may be added to the structure hereinabove described is illustrated in Figs. 7 and 8. This feature involves the placing of a plurality of openings 36 in the

lower part of the lower member 21 of the baseboard structure. When the holes or openings 36 are placed substantially as illustrated, they permit air to be forced outwardly parallel with the floor in addition to the air which will be entering the room and passing upwardly along the wall through the adjustable space between the upper and lower members of the baseboard.

These openings which permit a passage of the air parallel to the floor serve an entirely different purpose than baseboard registers heretofore known where slots or openings are provided, and are of a directional character causing the air to flow in the direction other than parallel with the floor. The combination of the openings 36 with the upward flow of warm air through the space between the baseboard members results in warm air passing upwardly substantially parallel with the wall and another flow of air parallel with the floor, thereby providing excellent coverage of the cold portion of the room.

While the openings 36 have been specifically illustrated as circular and as being located relatively close together, it will be understood that such openings may assume any desired size or shape to suit the needs of the particular construction without in any way departing from the spirit of the invention. It is further to be noted that these openings 36 may be used either with the construction shown in Fig. 4 or with that shown in Fig. 1, and may also be used either with or without the combination of the openings 35 shown in Fig. 6.

From the foregoing description, it will be apparent that a novel form of baseboard construction for perimeter heating has been designed which is useful in any dwelling where forced air is the heating medium regardless of the type of wall structure. It will also be evident that the construction is such that warm air entering the room may be evenly distributed over the entire wall area by properly regulating the adjusting means for the space in the faceplate through which the air must pass in order to enter the room. The construction is such that it may be economically manufactured and easily installed and overcomes the construction difficulties which have been experienced in the past, and which has prevented other perimeter heating arrangements from being readily adopted by the public.

Changes may be made in the form, construction and arrangement of parts from those disclosed herein without in any way departing from the spirit of the invention or sacrificing any of the attendant advantages thereof, provided, however, that such changes fall within the scope of the claims appended hereto.

The invention is hereby claimed as follows:

1. A baseboard construction for perimeter heating of an enclosed area having a floor and walls comprising an elongated back plate secured to the studding of the wall, the upper longitudinal edge of said plate terminating adjacent the lower edge of the wall spaced upwardly from the floor and the lower longitudinal edge of said plate terminating adjacent the edge of the floor, an upper face plate disposed forwardly of and spaced from said back plate and extending downwardly from the lower edge of the wall, the upper edge of said upper face plate being in contact with the wall, a lower face plate extending upwardly from the floor and spaced forwardly of said upper face plate, whereby air from behind said face plates will be directed into the room through the space therebetween, and means for varying said last named space to control the amount of air passing therethrough.

2. A baseboard construction for perimeter heating comprising an elongated back plate and a face plate spaced from said back plate, means closing the space between the upper and lower edges of said face plate and the upper and lower edges respectively of said back plate to provide an air conduit, said face plate including an upper member and a lower member spaced forwardly from said upper member and in overlapping relation therewith, means normally maintaining said members in spaced rela-

tion to permit passage of air therebetween, and means for varying the space between said members to control the amount of air passing therethrough.

3. A baseboard construction for perimeter heating of an enclosed area having a floor and walls comprising an elongated back plate, a forwardly extending portion at the upper edge thereof adapted to be located against the bottom edge of the wall spaced upwardly from the floor, a forwardly extending portion at the lower edge of said back plate adapted to be positioned adjacent the edge of a floor, an elongated face plate spaced forwardly of said back plate and cooperating therewith to provide an air conduit, said face plate including spaced apart upper and lower members, the lower member being spaced forwardly of said upper member, yieldable means for detachably securing said upper member in place adjacent the upper edge of said back plate, yieldable means for detachably securing said lower member in place adjacent the lower edge of said back plate, and means for varying the space between said members to control the amount of air passing therethrough from the conduit.

4. A baseboard construction for perimeter heating of an enclosed area having a floor and walls comprising an elongated back plate, a forwardly extending portion at the upper edge thereof adapted to be located against the bottom edge of a wall spaced upwardly from the floor, a forwardly extending portion at the lower edge of said back plate adapted to be positioned adjacent the edge of the floor, an elongated face plate spaced forwardly of said back plate and cooperating therewith to provide an air conduit, said face plate including spaced apart upper and lower members, the lower member being spaced forwardly of said upper member, a plurality of retainers mounted on the upper edge of said back plate and spaced along the length thereof for clamping a part of said upper member against the wall, means for detachably securing said lower member in place adjacent the floor and the lower edge of said back plate, and means for varying the space between said members to control the amount of air passing therethrough from the conduit.

5. A baseboard construction for perimeter heating of an enclosed area having a floor and walls comprising an elongated back plate, a forwardly extending portion at the upper edge thereof adapted to be located against the bottom edge of a wall spaced upwardly from the floor, a forwardly extending portion at the lower edge of said back plate having a lip thereon adapted to bear downwardly against the floor, an elongated face plate spaced forwardly of said back plate and cooperating therewith to provide an air conduit, said face plate including spaced upper and lower members, the lower member being spaced forwardly from said upper member, means for detachably securing said upper member in place adjacent the upper edge of said back plate, a rearwardly extending lip at the lower edge of said lower member adapted to be inserted between the lip on said back plate and the floor to detachably hold said lower member in place, and means for varying the space between said members to control the amount of air passing therethrough from the conduit.

6. A baseboard construction for perimeter heating of an enclosed area having a floor and walls comprising

an elongated back plate, a forwardly extending portion at the upper edge thereof adapted to be located against the bottom edge of a wall spaced upwardly from the floor, a forwardly extending portion at the lower edge of said back plate having a lip thereon adapted to bear downwardly against the floor, an elongated face plate spaced forwardly of said back plate and cooperating therewith to provide an air conduit, said face plate including spaced apart upper and lower members, a plurality of retainers mounted on the upper edge of said back plate and spaced along the length thereof for receiving a part of said upper member and clamping it against the wall, a rearwardly extending lip at the lower edge of said lower member adapted to be inserted between the floor and the lip on said back plate to detachably retain said lower member in place, and means for varying the space between said members to control the amount of air passing therethrough from the conduit.

7. A baseboard construction for perimeter heating of an enclosed area having a floor and walls comprising inner and outer face members mounted in spaced apart and overlapping relation, the upper edge of the inner member being against the wall and the lower edge of the outer member being against the floor, whereby air directed against one side thereof will pass through the space therebetween, a plurality of openings through said inner member in the area thereof overlapping said outer member to allow the outward passage of additional air, and means for varying said space to control the amount of air passing therethrough.

8. A baseboard construction for perimeter heating of an enclosed area having a floor and walls comprising inner and outer face members mounted in spaced apart and overlapping relation, the upper edge of the inner member being against the wall and the lower edge of the outer member being against the floor, whereby air directed against one side thereof will pass through the space therebetween, a plurality of openings through said inner member in the area thereof overlapping said outer member to allow the outward passage of additional air, and yieldable and adjustable means connected between said members for varying said space to control the amount of air passing therethrough.
